UNITED STATES PATENT OFFICE.

HERBERT T. HERR, OF PHILADELPHIA, PENNSYLVANIA, ASSIGNOR TO WESTINGHOUSE ELECTRIC AND MANUFACTURING COMPANY, A CORPORATION OF PENNSYLVANIA.

TURBINE BLADING.

Application filed May 31, 1922. Serial No. 564,890

To all whom it may concern:

Be it known that I, HERBERT T. HERR, a citizen of the United States, and a resident of Philadelphia, in the county of Philadelphia and State of Pennsylvania, have invented a new and useful Improvement in Turbine Blading, of which the following is a specification.

My invention relates to turbine blading, more particularly of the type wherein a relatively wide blade is adapted to receive steam transversely thereof and to discharge the same longitudinally thereof and it has for its object to provide blades of the character designated which shall be relatively light yet strong in construction.

In the accompanying drawing, Fig. 1 is a diagrammatic sectional view of a steam turbine embodying blading constructed in accordance with my invention; Fig. 2 is a transverse sectional view; and, Fig. 3 is a plan view of one of the novel blades indicated in Fig. 1.

In the application of Alexander T. Kasley, Serial No. 486,517, filed July 21, 1921, continued as Serial No. 521,872, filed December 12, 1921, and assigned to Westinghouse Electric and Manufacturing Company, there is disclosed a type of wide exhaust blade which is adapted to receive steam axially of the turbine rotor and to discharge it peripherally. It is characteristic of the type of blading disclosed in this application that each blade comprises a main portion, substantially plane in shape and disposed radially, and an outer curved or spoon-outline portion. In order to avoid the imposition of bending moments upon the main plane portion of these blades, it is necessary to design the outer curved discharge portion or tip so that the center of gravity thereof shall lie in the medial plane of the main blade portion; and, in order to obtain such a distribution of mass of each blade, as well as to provide for the design of an efficient fluid expanding channel at the blade tips, it has been necessary to increase the effective thickness at the point of maximum concavity. This necessary thickening has, in certain cases, led to the inclusion of an unnecessarily large and heavy mass of material in the tips with the imposition of severe centrifugal strains on the main portions of the blades when operated at high speeds.

Bearing in mind the necessity for a dis-

charge tip of relative thickness in order to provide a proper discharge channel and yet which shall at the same time not unduly strain the main portion of the blade, I find that it is desirable to construct the tip of two or more pieces of sheet metal defining a chamber therebetween, thus providing a structure which is light, strong, and susceptible of being so shaped as to give maximum economy.

Referring now to the drawings for a more detailed description of my invention, I show a turbine comprising a rotor 10, having journal portions 11, fitting in bearings 12, carried by the casing or cylinder 13, the casing or cylinder and the rotor being provided with energy-abstracting elements for abstracting energy from steam supplied from the conduit 14, and after the available energy is abstracted, the steam enters the exhaust chamber 15 which communicates with a suitable exhaust outlet, not shown.

I show the conduit 14 communicating with one or more nozzles 17 of a multi-velocity impulse stage comprising moving rows of blades 18, carried by the rotor 10, and a row of redirecting blades 19 interposed therebetween. After being discharged from the last row of moving blades 18, the steam is then fractionally expanded by the stages comprised by the stationary and moving rows of blades 20 and 21 carried by the cylinder or casing 13 and the rotor 10, respectively; and after being discharged from the last row of moving blades 21, the steam then passes between the guide blades 22 for entry between the wide exhaust blades 23, from which it is discharged peripherally to the exhaust chamber 15. The particular construction of the blading 18, 19, 20 and 21, constitutes no part of my invention and it is referred to for illustrative purposes only.

The wide exhaust blades 23 comprise inner substantially radial or plane portions 24 and outer curved or spoon-outline discharge portions 25, the latter being adapted to expand and discharge the fluid peripherally at a small angle. The blades 23 are preferably made up of a plurality of side-by-side sections 27 as indicated in Fig. 1 in order to facilitate manufacture.

The outer curved portions 25 are formed of two pieces of sheet metal 28 and 29 bent to the appropriate shape as shown, these two pieces of metal being appropriately

joined as by welding or brazing at the extreme tip of the blade and engaging the main portion 24 of the blade on opposite sides thereof as shown at 30. Preferably, 5 the engaging faces are serrated as shown at 31 and rivets 32 are placed therethrough in order to firmly attach the tip of the main portion of the blade.

Suitable lashing members may be provided in the form of edge wound ribbons 34 10 suitably seated between adjacent blade sections, these members being rigidly fastened, as by brazing, soldering or riveting, so as to largely eliminate vibration.

15 While I have disclosed the hollow blade tip as being formed from two pieces of sheet metal it will be obvious that it might equally well be formed by the suitable shaping of a single piece of metal and the resultant tip may be attached to the main blade portion in a plurality of different ways.

20 While I have shown my invention in but one form, it will be obvious to those skilled in the art that it is not so limited, but is susceptible of various other changes and modifications, without departing from the spirit thereof, and I desire, therefore, that only such limitations shall be placed thereupon as are imposed by the prior art or as 25 are specifically set forth in the appended claims.

30 1. In a steam turbine rotor blade, the com-

binati³⁵on with a plane body portion, of a spoon-outline tip portion thereupon, said tip portion being hollow in construction and embracing the tip of said body portion.

2. In a steam turbine rotor blade, the combination with a plane body portion, of a spoon-outline tip portion thereupon, said tip portion being formed from two pieces of sheet metal joined at their outer edge and embracing the tip of said plane portion at their inner edges, said pieces of sheet metal defining a hollow space within said tip portion. 40 45

3. In a steam turbine rotor blade, the combination with a plane body portion, of a spoon-outline tip portion thereupon, said tip portion being hollow in construction and 50 embracing the tip of said body portion, and fastening means for joining said tip portion to said body portion.

4. In a turbine rotor construction, a series of blades having main plane body portions lying in radial planes and with thickened spoon-shaped tips defining exhausting throats, said blades being adapted to receive fluid axially of the rotor and to exhaust the same radially through said throats, and said tip portions being formed hollow to minimize the weight thereof. 55 60

In testimony whereof, I have hereunto subscribed my name this 25th day of May, 1922.

HERBERT T. HERR.
